(57) **CLAIM**

The ornamental design for a battery plate, as shown and described.

DESCRIPTION

FIG. 1 is a front left top perspective view of a first embodiment of a battery plate showing my new design;

FIG. 2 is a left-side view thereof;

FIG. 3 is a right-side view thereof;

FIG. 4 is a back view thereof;

FIG. 5 is a front view thereof;

FIG. 6 is a top view thereof;

FIG. 7 is a bottom view thereof;

FIG. 8 is an enlarged fragmentary view thereof showing the left-side of the battery plate;

FIG. 9 is an enlarged fragmentary view thereof showing the top of the battery plate;

FIG. 10 is a front right top perspective view of a second embodiment of a battery plate;

FIG. 11 is a right-side view thereof;

FIG. 12 is a left-side view thereof;

FIG. 13 is a back view thereof;

FIG. 14 is a front view thereof;

FIG. 15 is a top view thereof;

FIG. 16 is a bottom view thereof;

FIG. 17 is an enlarged fragmentary view thereof showing the right-side of the battery plate; and,

FIG. 18 is an enlarged fragmentary view thereof showing the top of the battery plate.

The second embodiment is a mirror image of the first embodiment reflected across the front-back axis. The broken lines in the drawing represent portions of the battery plate that form no part of the claimed design.
